UNITED STATES PATENT OFFICE.

RICHARD BRAUN, OF KARLSRUHE, GERMANY, ASSIGNOR TO THE NATIONAL CASH REGISTER COMPANY, OF DAYTON, OHIO, A CORPORATION OF OHIO, (INCORPORATED IN 1906.)

CASH-REGISTER.

1,044,482.

Specification of Letters Patent. Patented Nov. 19, 1912.

Application filed May 28, 1908. Serial No. 436,055.

To all whom it may concern:

Be it known that I, RICHARD BRAUN, a subject of the German Emperor, residing at Karlsruhe, in the German Empire, have 5 invented new and useful Improvements in and Relating to Cash-Registers, of which the following is a specification.

This invention relates to cash registers and has for its main object the provision of 10 mechanism for giving an additional check on the operator thereby compelling correct operations of the machine. Machines of this type have been provided with indicating devices which indicate the amount of transactions entered therein and this indicating mechanism is undoubtedly of value, but it sometimes happens that purchasers are not where they can see the indication so that the value of this feature is sometimes lost. 15 The present invention aims to compel the purchaser to come to the cash register and obtain his change or his receipt and thereby in effect compels him to see that the amount registered and indicated is correct. To this end there has been provided in connection with a machine of a well known type, an additional set of indicators shown as at the side of the machine, and directly adjacent and over these auxiliary indicators is a substantially horizontal tray on which it is intended the money for change or the receipt shall be placed by the operator. The money tray has a transparent portion through which the auxiliary indicators may be seen, 30 so that the purchaser when taking up his change cannot help seeing the indicators directly below the change, and will thereby notice if the amount registered and indicated differs from the amount which he has paid.

With these and incidental objects in view, the invention consists in certain novel features of construction and combinations of parts, the essential elements of which are 45 set forth in appended claims, and a preferred form of embodiment of which is hereinafter described with reference to the drawings which accompany and form part of the specification.

50 Figure 1 is a perspective view of the machine showing the attachment applied thereto. Fig. 2 is a vertical section of the register.

55 The auxiliary device is shown in connection with a machine of a well known type,

but it will be understood that this is merely for illustration and that the utility of the invention is not limited to this type of machine.

In the drawings the cash register *a* is 60 provided with a casing *c* at the side thereof forming a receptacle and the top of which *b* is the cash or money tray. As shown this tray is substantially horizontal though the center is slightly depressed whereby the 65 money will be retained thereon.

As usual in cash registers, main indicators *f* are provided, adapted to be moved in any desired way from manipulative devices such as the levers shown in the drawings, through 70 racks *n* gearing with pinions *n'* which are fast to the said indicators. Beside each gear *n'* and rigidly connected thereto are gears *g* which are really chain pulleys and over which chains *m* run. These chains 75 are connected with chain pulleys *k* at the lower ends thereof, these latter pulleys being fast on nested sleeves *i'*, etc., which surround a rod *l* carried by bearings *h*. On the other end of the nested sleeves *i'*, etc., 80 are the auxiliary indicators *d* shown as cylinders or wheels and having numbers on their peripheries.

It will be seen that through the gearing just described the auxiliary indicators *d* 85 will at all times exhibit through the opening *e* of the money tray *b* the precise amount indicated by the main indicators *f*, so that each purchase is shown by the auxiliary indicators as well as by the main indicators, 90 the chain and chain pulleys together with the nested sleeves forming positive and permanent connections from the indicator driven gears *g* to the auxiliary indicators *d*. Of course, other gearing may readily be 95 employed but the type shown, including sprocket wheels and chains, is effective.

From this description it will be seen that the object first stated is well attained by this construction. The auxiliary indicators *d* at each operation of the machine indicate the amount of the purchase, and the customer to obtain his change or receipt must come to the register and take his change or receipt from the money tray, but it will be impossible for him to do so without observing the auxiliary indicators through the transparent portion of the coin tray. Therefore the operator will be very careful to register the correct amount and will not 110

dare attempt to register an amount smaller than that actually paid.

I claim--

- 5 1. In a cash register, the combination with a set of auxiliary indicators, and a money tray having a window through which said auxiliary indicators may be viewed, of a set of main indicators, and positive permanent connections between the two sets of indicators.
- 10 2. In a cash register, the combination with a set of auxiliary indicators, and a money tray having a window through which said auxiliary indicators may be viewed, of a set of main indicators, with means for positioning said main indicators, and positive permanent connections whereby the auxiliary indicators are driven by the main indicators.
- 15 3. In a cash register, the combination with a set of auxiliary indicators, and a money tray having a substantially horizontal transparent portion through which said auxiliary indicators may be viewed, of a set of main indicators, means for positioning said main indicators, and positive gear connections between said two sets of indicators, whereby the auxiliary indicators may be driven by the main indicators.
- 20 4. In a cash register, the combination with a set of auxiliary indicators, and nested sleeves to which said indicators are

fast, of a money tray having a substantially horizontal transparent portion through which said auxiliary indicators may be viewed, a set of main indicators, gears movable therewith, and means positively and permanently connecting said gears to said nested sleeves.

5 5. In a cash register, the combination with a set of auxiliary indicators, of a money tray having a transparent portion through which said indicators may be viewed, and permanent connections from said indicators to movable parts of the cash register.

6. In a cash register, the combination with a set of main indicators, and sprocket wheels fast thereto, of a set of auxiliary indicators, nested sleeves fast to said auxiliary indicators, a sprocket wheel mounted on each nested sleeve, means connecting said main indicator sprocket wheels to the nested sleeve sprocket wheels, and a money tray having a transparent portion through which said auxiliary indicators may be viewed.

In witness whereof I have hereunto set my hand in presence of two witnesses.

RICHARD BRAUN.
